THERAPEUTIC DEVICE

Robert W. Hodgson, Sherman Oaks, Calif., assignor to Herman S. Pierce, Los Angeles, Calif.

Application September 4, 1945, Serial No. 614,359

2 Claims. (Cl. 250—36)

1

This invention relates broadly to an oscillation generator and relates in particular to an apparatus for treatment of nerves and muscles by means of electric impulses, especially for artificial invigoration and stimulation of muscles for therapeutic purposes.

Therapeutic devices capable of generating currents of varying potential have been used for the treatment of various physiological disturbances. The apparatus employed heretofore has been extremely complex, required the use of a large number of electronic tubes, and was provided with so many controls, indicators and the like that a patient could not procure the equipment and use it for self-treatment due to the dangers involved in handling apparatus capable of generating a tremendous range of frequencies of various potentials. The present invention is particularly directed to a simple and compact apparatus which may be built economically so as to generate or produce a current of the desired characteristics or a current falling within relatively narrow limits of variation, so that an individual patient may keep the apparatus at his home for self-treatment.

Furthermore, the apparatus of the present invention is relatively foolproof, the terminals from the apparatus being virtually interchangeable without destroying the efficacy of the current supplied to the electrodes.

It is an object of the present invention to provide a simple, small, compact and economical apparatus which will produce a therapeutic current giving better, quicker and more lasting results than those currents now employed therapeutically for a similar purpose.

It is a further object of the invention to provide an apparatus which will produce a therapeutic current which will cause nerve excitation and propagation with the minimum power dissipation in the form of heat created in the body tissues.

Another object of the invention is to provide an apparatus for producing a therapeutic current, the current comprising separate pulsations spaced apart by periods of rest, the duration of the pulsations and the duration of the periods of rest between the pulsations being such as to cause nerve excitation and propagation with the minimum power dissipation in the form of heat created in the body tissues and without causing tetany in the muscle being treated.

Further objects of the invention include the provision in the device of means for intermittently interrupting the wave train and also mod-

2

ulating said wave train, each function being independently controlled.

Further objects and advantages of the invention will be brought out in the following part of the specification.

Referring to the drawings, which are for illustrative purposes only:

Fig. 1 is a schematic electrical circuit diagram showing a preferred embodiment of the device for producing the novel therapeutic current.

Fig. 2 is a schematic electrical circuit diagram showing a second embodiment of the device.

Fig. 3 is a schematic electrical circuit diagram showing a third embodiment of the device.

15 In the preferred form of my device shown in Fig. 1, an alternating current supply circuit, such as the common 110 volt alternating current commercial system, feeds the primary winding 1 of a transformer 2. One end of the secondary winding 3 of the transformer 2 is connected by a conductor 4 with one anode 5 of a full wave rectifying electron tube 6. The other end of the secondary winding 3 of the transformer 2 is connected by a conductor 7 with the other anode 8 of the full wave rectifying electron tube 6. A center tap 9 of the secondary winding 3 of the transformer 2 is connected to ground at 10. Another secondary winding 11 of the transformer 2 is connected by conductors 12, 13, and 14 with the filament 15 of the full wave rectifying electron tube 6 and by conductors 16 and 17 with the filament 18 of the electron tube 19 for energizing said filaments. The filament 15 of the full wave rectifying tube 6 is connected by conductors 13 and 20 25 with a choke coil 21, which is connected by conductors 22 and 23 with a filter condenser 24, which is connected to ground at 25 by conductors 26 and 27. The choke coil 21 is also connected by conductors 22 and 28 with load resistor 29, which is connected with the anode 30 of the electron tube 19 by conductor 31.

The choke coil 21 is also connected by conductors 22, 28, and resistor 32 to the screen grid 33, which is connected to ground at 25 by conductor 45 34, condenser 35 and conductor 27. The anode 30 of the electron tube 19 is also connected to ground at 25 by conductors 31 and 36, the primary winding 37 of the transformer 38, condenser 39, and conductors 40, 26, and 27. The 50 control grid 41 of the electron tube 19 is connected to ground at 25 by a resistor 42 and a conductor 43, in parallel with conductor 44, secondary winding 45 of the transformer 38, condenser 46, and conductors 47, 40, 26 and 27. The 55 cathode 48 of electron tube 19 is connected

to ground at 25 by a resistor 49 shunted by a condenser 50. The anode 30 of electron tube 19 is also connected to ground at 25 by conductor 51, condenser 52, potentiometer 53, and conductors 54, 47, 40, 26 and 27. The output lead 55 of the potentiometer 53 is interrupted by a switch 56 which is mechanically connected to a switch 57 of an intermittent action, electromagnetic time delay relay 58, one terminal of which is connected in series with the switch 57, the conductor 59, the resistor 65, and the choke coil 21, and the other terminal of which is grounded at 60. The relay 58 is shunted by condenser 61.

The device operates as follows:

When alternating current flows in the primary winding 1 of the transformer 2, a current is induced in the secondary winding 11 which energizes the filaments 15 and 18 of the full wave rectifying electron tube 6 and the electron tube 19 respectively. A flow of current is also induced in the secondary winding 3 which is rectified by full wave rectifying electron tube 6 in a manner well known in the art. This rectified current is then filtered by choke coil 21 and filter condenser 24 in a manner also well known in the art.

The greater the current flow through electron tube 19, the less positive the anode 30 becomes with respect to ground, and conversely, the lesser the current flow through electron tube 19, the more positive the anode 30 becomes with respect to ground. With the potential of the anode 30 thus fluctuating with respect to ground, there is a corresponding current flow in a direction determined by the fluctuation of the potential of the anode 30, through primary winding 37 of transformer 38 and into or out of condenser 39. This current flow through the primary winding 37 of the transformer 38 induces a current flow through the secondary winding 45 of the transformer 38 which charges condenser 46 with the same polarity as condenser 39. Thus as greater current flows through the electron tube 19, a greater positive potential is applied to the control grid 41, which in turn allows a greater current to flow through the electron tube 19, thus giving an extremely rapid rise in the current flowing through the electron tube 19 until saturation current is flowing through the electron tube 19.

As soon as the condenser 39 becomes charged to a potential equal to the potential of the anode 30 when saturation current is flowing, all of the current flow through the primary winding 37 of the transformer 38 ceases. As soon as the potential of condenser 46 becomes greater than the induced potential across the secondary winding 45 of the transformer 38, which is of opposite polarity, the condenser 46 begins to discharge current in a direction opposite to the previous current flow through the secondary winding 45 of the transformer 38. This applies a negative potential to the grid 41, which reduces the current flow through the electron tube 19 which, in turn, causes the anode 30 of the electron tube 19 to become more positive, which causes an oppositely directed current flow through the primary winding 37 of the transformer 38 which, in turn, induces a current flow through the secondary winding 45 of the transformer 38, supplementing the current flow resulting from the discharge of condenser 46, thus causing the current flow through the electron tube 19 to drop abruptly. It should be noted that the current flow through the primary winding 37 of the transformer 38 caused by the more positive potential of the anode 30 of the electron tube 19, resulting from the reduction in

current flowing through the electron tube 10, induces a voltage across the secondary winding 45 of the transformer 38, which acts to effectively charge the condenser 46 through the resistance 42 to a polarity opposite to that which said condenser has previously had. The screen grid 33, associated condenser 35, resistor 32, and the biasing resistor 49 shunted by the by-pass condenser 50 all function in a manner well known in the art. The resistor 42 controls the rate of charging and discharging of the condenser 46.

The operation of the device described to this point will result in a series of unidirectional, flat-topped pulsations of substantially rectangular wave form across the load resistor 29. A differentiating circuit comprising conductor 51, condenser 52, potentiometer 53, and conductors 54, 47, 40, 26 and 27 differentiates said rectangular pulsations in a manner well known in the art and produces in potentiometer output lead 54 a series of pulsations sharply peaked in one direction. The potentiometer output lead 55 is intermittently interrupted by the switch 56, which is mechanically connected to the switch 57 of the intermittent action electromagnetic time delay relay 58. The switch 57 is normally held in contact with the contact point 62 by a spring (not shown). The current flows through the conductor 59, the resistor 65, contact point 62, switch 57 and into condenser 61 until said condenser is charged to a sufficiently high potential to cause the relay 58 to attract the switch 57 and break the circuit. The circuit will be brought back to its normal position in contact with the contact point 62 by a spring (not shown), when the condenser 61 has discharged to a point where the potential on said condenser has dropped to a value less than the holding voltage necessary for the relay 58 to hold the switch 57.

In a second embodiment of the invention, shown in Fig. 2, the switch 56' is placed in the power circuit, for example, in conductor 22', and varying degrees of modulation of the wave train are achieved by varying the time constant of the power supply filter comprising choke coil 21' and filter condenser 24' so as to cause the series of pulsations to have a gradually increasing amplitude up to the maximum value and then have a gradually decreasing amplitude until the wave train is interrupted by the switch 56'. This takes place by reason of the fact that the positive potential at the anode 30' of the electron tube 19' is intermittently interrupted by means of the switch 56', which is positioned in the lead 22' prior to the juncture therewith of the filter condenser 24'. Thus, when the switch 56' interrupts the circuit, a progressively decreasing positive potential is applied to the anode 30', which decreases at a rate dependent upon the time constant of the filter condenser and the circuit. This causes the oscillations generated to progressively decrease in amplitude also. When the switch 56' is closed, the positive potential applied through the choke filter comprising the choke coil 21' and the filter condenser 24' is progressively built up, which causes the oscillations generated in the oscillation generator to also have a progressively increasing amplitude. The rate of this modulation or building up and decline of the oscillations generated in the oscillation generator may be varied by varying the time constant of a power supply filter.

Under some circumstances a rectangular wave form may be the most desirable and in this connection it is to be understood that the differen-

tiating circuit shown in Fig. 1, comprising conductor 51, condenser 52, potentiometer 53, may be dispensed with entirely, and as shown in Fig. 3 load resistor 29 may be replaced by a potentiometer 29'' and potentiometer output lead 55'' may be placed in contact with the potentiometer 29''. The switch 56'' may be placed in the potentiometer output lead 55'' or in the power circuit, for example, conductor 28'', as hereinabove set forth.

The apparatus may be used in supplying electric impulses to various electrodes applied to the human body for therapeutic purposes. It has been used with particular success in relieving congestion of the prostate.

When used in prostate treatment, an electrode is provided with means limiting its introduction into the anus to a desired depth only, and an insulating sleeve which exposes only a desired, round-nosed electrode to contact with the membranes. This electrode is usually connected to terminal 63 of the device, whereas terminal 64 is usually connected to another electrode, preferably in the form of a moistened pad which is placed over the sacrum. However, the first mentioned electrode may be connected to terminal 64 and the second mentioned electrode may be connected to terminal 63. In these prostate treatments, a current consisting of a series of sharply peaked pulsations of approximately $\frac{1}{150}$ to $\frac{1}{100}$ second duration per pulsation and spaced apart by periods of approximately $\frac{1}{5}$ to $\frac{1}{6}$ second duration per period and intermittently interrupted approximately every $\frac{2}{3}$ to 1 second by a period of inactivity of approximately $\frac{2}{3}$ to 1 second and having an amplitude selectively variable between zero and approximately 180 volts peaks was found satisfactory.

Such characteristics are attained by the use of components of the following values:

42—5.75 megohms	24—8 microfarads
49—300 ohms	39—0.02 microfarad
29—50,000 ohms	46—0.02 microfarad
32—25,000 ohms	52—0.02 microfarad
65—6,000 ohms	61—250 microfarads
53—0.25 megohm	58—60 volts, 5000 ohms
50—8 microfarads	21—15 henries
35—0.1 microfarad	

The foregoing description serves merely to illustrate by specific applications the principles of my invention and should not be taken as defining the scope thereof. The oscillation generator described herein, is referred to in the claims as a self-excited feed back type, relaxation, electric oscillation generator adapted to generate non-sinusoidal unidirectional electric oscillations of virtually rectangular wave form. This is understood to mean the type of oscillator wherein the frequency of the output oscillations is determined by an RC circuit and wherein there is a definite feed back from the output to the input. The wave form may vary from virtually rectangular to various other non-sinusoidal, unidirectional wave forms, and all such are to be understood to be included in the scope hereof.

I claim:

1. In a device adapted to generate therapeutic current, a feed back, self-excited, relaxation-type, single vacuum tube, electric oscillation generator adapted to generate non-sinusoidal, unidirectional electric oscillations without requiring an input signal from an external source, comprising: a thermionic electron tube means having a cathode, an anode and the control grid;

an anode circuit connecting said anode and cathode in series and having a load impedance therein; a feed back transformer having a primary winding and a secondary in inductive relation; a condenser connecting one end of said primary winding to said cathode, the other end of said primary winding being connected to the anode; a grid biasing control circuit including a resistance and a capacitance, electrically connected to said secondary winding; said control grid and said cathode being connected to said control circuit so as to be on each side of said resistance; said feed back transformer and the load impedance in the anode circuit which causes a pulsating potential to be applied to the primary winding, being such as to cause the secondary winding to alternately apply a negative potential to said grid sufficiently large to block the flow of current through the electron tube, and a positive potential sufficiently large to cause saturation current to flow through said electron tube at a frequency determined by the time constant of the resistance and capacitance in the grid control circuit; an intermittent interrupting means arranged to effectively, intermittently interrupt the output oscillations of the oscillation generator, comprising a relay shunted by a condenser connected to the anode circuit through a resistance, said relay being arranged to simultaneously open a switch in said anode circuit in series with a power supply filter and a switch in series with said relay which is normally spring biased into closed position, thus de-energizing the relay and allowing said switches to close, which causes the relay to be energized again and open the switches intermittently in a manner dependent upon the time constant of said interrupting means whereby the oscillations generated by the oscillation generator are caused to increase to a maximum and decrease to a minimum upon opening and closing of said switch at a rate of increase and decrease dependent upon the time constant of the power supply filter.

2. In a device adapted to generate therapeutic current, a feed back, self-excited, relaxation-type, single vacuum tube, electric oscillation generator adapted to generate non-sinusoidal, unidirectional electric oscillations without requiring an input signal from an external source, comprising: a thermionic electron tube means having a cathode, an anode and the control grid; an anode circuit connecting said anode and cathode in series and having a load impedance therein; a feed back transformer having a primary winding and a secondary winding in inductive relation; a condenser connecting one end of said primary winding to said cathode, the other end of said primary winding being connected to the anode; a grid biasing control circuit including a resistance and a capacitance, electrically connected to said secondary winding; said control grid and said cathode being connected to said control circuit so as to be on each side of said resistance; said feed back transformer and the load impedance in the anode circuit which causes a pulsating potential to be applied to the primary winding, being such as to cause the secondary winding to alternately apply a negative potential to said grid sufficiently large to block the flow of current through the electron tube, and a positive potential sufficiently large to cause saturation current to flow through said electron tube, at a frequency determined by the time constant of the resistance and capacitance in the grid control circuit; differentiating circuit means arranged to differentiate the oscil-

lations generated by the oscillation generator; an intermittent interrupting means arranged to effectively, intermittently interrupt the output oscillations of the oscillation generator, comprising a relay shunted by a condenser connected to the anode circuit through a resistance, said relay being arranged to simultaneously open a switch in said anode circuit in series with a power supply filter and a switch in series with said relay which is normally spring-biased into closed position, thus de-energizing the relay and allowing said switches to close, which causes the relay to be energized again and open the switches intermittently in a manner dependent upon the time constant of said interrupting means whereby the oscillations generated by the oscillation generator are caused to increase to a maximum and decrease to a minimum upon opening and closing of said switch at a rate of increase and decrease dependent upon the time constant of the power supply filter.
